[57] CLAIM

I claim the ornament design for a doll jewelry box with music, as shown.

DESCRIPTION

FIG. 1 is a front view of a doll jewelry box with music showing my new design;

FIG. 2 is a rear view of the doll jewelry box with music;

FIG. 3 is a right side view of the doll jewelry box with music;

FIG. 4 is a left side view of the doll jewelry box with music; and,

FIG. 5 is a combined bottom view of the doll lid, and top view of the base of the box.
